(57) **CLAIM**

The ornamental design for a front bezel of a document validator, as shown and described.

DESCRIPTION

FIG. 1 is an isometric view of a front bezel of a document validator according to a first embodiment of my design.

FIG. 2 is a front view thereof.

FIG. 3 is a right side view thereof.

FIG. 4 is a left side view thereof.

FIG. 5 is a top view thereof.

FIG. 6 is a bottom view thereof.

FIGS. 7 through 12 are, respectively, isometric, front, right side, left side, top and bottom views according to a second embodiment of my design which shows all of the alternative features; and,

FIGS. 13 through 18 are, respectively, isometric, front, right side, left side, top and bottom views according to a third embodiment of my design which shows all of the alternative features.
